UNITED STATES PATENT OFFICE.

WILLIAM A. LEWIS, OF ASHTABULA, OHIO.

BUCKET UNLOADER.

Application filed March 23, 1925. Serial No. 17,494.

To all whom it may concern:

Be it known that I, WILLIAM A. LEWIS, a citizen of the United States, residing at Ashtabula, in the county of Ashtabula and State of Ohio, have invented a certain new and useful Improvement in Bucket Unloaders, of which the following is a full, clear, and exact description.

This invention relates to an improvement in unloaders of the bucket type in which the grab bucket employed for gathering up loose material from the hold of a vessel is so mounted that one of the sections of the bucket has an extended range of lateral movement with respect to the supporting leg for gathering up loose material on the floor of the hold.

A type of unloader which is at the present time being extensively used is one in which the bucket is supported at the lower end of a rigid vertical leg in such manner that after the bucket has been opened it may be shifted laterally of the leg to position one of the sections of the bucket at a considerable distance of the axis of the leg to clean up the material remaining near the sides of the hold after most of the material has been removed.

The floors of the holds of vessels as usually constructed are slightly higher along the center and inclined toward the opposite sides of the hold. In addition to the crown of the floor above referred to, the vessel being unloaded may have a list which causes the floor to lie at an inclination to the horizontal. Under such conditions it has heretofore been found impossible to completely clean up the low side of the vessel with the bucket owing to the fact that the scraping edges of the bucket when opened normally lie in the same horizontal plane so that the scraping edge of the extended section when moving to closed position over the floor at the low side of the hold travels above the surface of the floor, leaving some of the material on the floor.

The present invention has for its object to provide an unloader bucket in which the scraping edges of the bucket sections may be maintained in engagement with the floor during closing movements regardless of whether the floor is level or inclined with respect to the horizontal so that the floor may be completely cleaned by the unloader bucket.

The accompanying drawings and following description set forth in detail certain means embodying the invention, the disclosed means, however, constituting but one of the various mechanical forms in which the principle of the invention may be employed.

Reference should be had to the accompanying drawing, forming a part of this specification, in which Fig. 1 is a side elevation of the lower portion of the vertical supporting leg and the bucket thereon, said bucket being shown in full lines in closed position and in dotted lines in full open and laterally shifted positions; Fig. 2 is a side elevation looking toward the back of one of the bucket sections.

Referring to the accompanying drawings, the rigid bucket supporting leg is indicated by the numeral 1 and the two sections of the grab bucket are indicated by the numerals 2 and 3. The bucket sections 2 and 3 are rigidly secured to the lower ends of rigid arms 4 which are pivoted at their upper ends on a transverse shaft 5. The pivot shaft 5 of the bucket supporting arms is guided for vertical movement in guideways 6 on opposite sides of the supporting leg 1. Mounted on the lower end of the leg 1 there is a pulley supporting and guide portion 7 which has a lateral extension 8 at one side. Within the lower portion 7 of the leg at opposite sides thereof are horizontal guideways 9 in which rollers 10 journaled on the arms 4 of the bucket travel. Mounted centrally of the guide portion 7 there is a horizontally sliding beam 11 which is connected by a connecting rod 12 with the outer end of the arm 4 to which the bucket section 3 is attached. An opening chain 13 is attached at one end to the end of the beam 11 which is over the bucket section 2, passes over a guide sheave 14 in the extension 8 of guide member and under a pulley 15 on the guide member adjacent the center thereof, said opening chain extending upwardly within the leg to a suitable hoist drum. When the chain 13 is wound up, the beam 11 is shifted laterally causing the section 3 of the bucket to swing outwardly moving the pivot 5 downwardly in the vertical guides 6 which causes the rollers 10 carried by the arm 4 supporting the section 2 to travel outwardly in the guideway 9 moving the section 2 of the bucket outwardly at the same rate as

- the section 3. A pair of closing chains 16 are attached to the outer ends of the supporting arms 4 adjacent opposite sides of the bucket sections 2 and 3, said closing 5 chains passing under guide sheaves 17 journaled on the lower portion 7 of the leg adjacent the center thereof and passing upwardly along opposite sides of the leg to suitable hoist drums.
- 10 The laterally extending guide portion 8 has a telescopic extension 18 which is adapted to form a continuation of the horizontal guideways 9. The telescopic extension 18 is normally held in retracted position by 15 a spring latch 19 which is adapted to be released to permit the telescopic extension to move to extended position. When the opening chain 13 is wound up, the two bucket sections are moved apart at equal 20 rates of speed until the sections are in fully extended positions as designated at —a— in Fig. 1. When in this position the roller 10 carried by the arm supporting the bucket section 3 is in engagement with the end of of 25 the telescopic extension 18 and the arm 4 is in substantially horizontal position passing through the open end of the extension 18. The end of the extension 18 carries a vertical trip pin 20 which is adapted to be 30 pushed upwardly by the arm 4 which moves up into the open end of the extension, in its opening movement the pin 20 being engageable with the latch 19 to push the same to releasing position. If after the bucket has 35 been moved to the extended position —a—, a further movement be imparted to the beam 11, the latch 19 will be released and the rollers 10 on the arm 4 will push the extension 18 outwardly, the two sections of the 40 bucket being then shifted laterally in the same direction to the position indicated at —b— in Fig. 1 to enable the section 3 to operate at a considerable distance laterally of the supporting leg 1.
- 45 The bucket sections 2 and 3 are so mounted upon the arm 4 that when the bucket is in closed position they abut along a line —c— which is offset laterally with respect to a vertical plane —d— which passes 50 through the pivot 5 of the arms 4 and bisects the angle between the arms. The offsetting of the meeting edges of the bucket with respect to the center plane of the bucket causes the scraping edge 22 of the section 3 of the bucket to normally lie in all open positions below the scraping edge 21 of the section 2 so that when the section 3 is extended over the low portion of a floor which is inclined with respect to the horizontal, it can engage 55 with the floor throughout the closing movement. The mounting of the bucket sections permits the section 3 to yield in an upward direction so that the section 3 may scrape along a horizontal floor or along the floor 60 at the high side of the hold when the sec-
- tion 3 is operating on the high side thereof. The amount of lateral offset of the bucket section with respect to the centerplane of the bucket is made sufficient to provide for the maximum difference in level between the 70 central portion of the hold and outer side thereof encountered in ordinary working conditions, so that, regardless of whether the floor of the hold is horizontal or inclined, the material can be completely 75 cleaned up.
- Having described my invention, I, claim—
1. An unloader comprising a rigid vertical supporting leg, a grab bucket at the 80 lower end of the leg which consists of laterally movable sections adapted to be spread apart and moved to closed position to gather a load from the floor of the hold of a vessel, said sections being so mounted that the scraping edges thereof when the buckets are spread apart are positioned at different levels whereby the scraping edges of both sections may be maintained during the closing movement in engagement with a floor 85 inclined with respect to the horizontal, and means for operating the bucket.
2. An unloader comprising a rigid vertical supporting leg, a grab bucket at the lower end of the leg which consists of laterally movable sections adapted to be swung about a common axis one with respect to the other from open to closed position, said sections having scraping edges which abut 90 when the sections are in closed position and said sections being so mounted that one section is yieldably held when the sections are spread apart, in a position such that its scraping edge is lower than the scraping edge of the other section whereby both sections may be maintained during closing movement in engagement with a floor inclined with respect to the horizontal, and means for operating the bucket.
3. In an unloader, a rigid vertical supporting leg, a grab bucket at the lower end of the leg which consists of a pair of laterally movable sections adapted to be spread apart, one of said sections being mounted 100 for bodily movement laterally to a position farther from the boom than the other section, said sections having scraping edges adapted to engage with a floor during closing movement and which abut when the bucket is closed, said sections being so mounted that when the sections are extended the first mentioned section is yieldably supported with its supporting edge normally lying at a lower level than the scraping edge 105 of the other section whereby the scraping edges of the two sections may be maintained in continuous engagement during the closing movement with a floor inclined with respect to the horizontal, and means for 110 operating the bucket.
4. In an unloader, a rigid vertical supporting leg, a grab bucket at the lower end of the leg which consists of a pair of laterally movable sections adapted to be spread apart, one of said sections being mounted 115 for bodily movement laterally to a position farther from the boom than the other section, said sections having scraping edges adapted to engage with a floor during closing movement and which abut when the bucket is closed, said sections being so mounted that when the sections are extended the first mentioned section is yieldably supported with its supporting edge normally lying at a lower level than the scraping edge 120 of the other section whereby the scraping edges of the two sections may be maintained in continuous engagement during the closing movement with a floor inclined with respect to the horizontal, and means for 125 operating the bucket.
5. In an unloader, a rigid vertical supporting leg, a grab bucket at the lower end of the leg which consists of a pair of laterally movable sections adapted to be spread apart, one of said sections being mounted 130 for bodily movement laterally to a position farther from the boom than the other section, said sections having scraping edges adapted to engage with a floor during closing movement and which abut when the bucket is closed, said sections being so mounted that when the sections are extended the first mentioned section is yieldably supported with its supporting edge normally lying at a lower level than the scraping edge of the other section whereby the scraping edges of the two sections may be maintained in continuous engagement during the closing movement with a floor inclined with respect to the horizontal, and means for operating the bucket.

4. In an unloader, a rigid vertical supporting leg, a grab bucket at the lower end of the leg which consists of a pair of arms pivoted at their upper ends and carrying bucket sections at their lower ends, means on the leg for guiding the pivot of the arms along the axis of the leg during opening movement and laterally of the leg when the arms extended to position one of the sections of the bucket at a greater distance from the axis of the leg than the other, said
- 5
- 10
- 15
- bucket sections having scraping edges which abut when the bucket is closed along a line offset laterally with respect to the plane bisecting the angle between said arms, and means associated with the leg for operating the bucket and for shifting the same laterally when in open position.

In testimony whereof, I hereunto affix my signature.

WILLIAM A. LEWIS.
